COMBINED WINDOW AND SCREEN

Louis Royak, New York, N. Y.

Application June 13, 1944, Serial No. 540,090

3 Claims. (Cl. 160—28)

1

This invention relates to new and useful improvements in windows.

More specifically, the present invention proposes the construction of a window of novel construction having one or more sashes which may be slid vertically to open and closed position and which may be swung to open and closed position.

Still further, the invention proposes a window as aforesaid having weather stripping.

Still further, it is proposed to provide a sash for a window, including windows of the aforementioned type provided with a spring counterbalance on one side and a pulley counterbalance or brake on the other side.

Still further it is proposed to provide a window with an automatically operable screen which screens any opening of the window.

A further object of the present invention is to provide a window having two sashes, one of which is provided with means wiping and sealing against the other sash.

A further object is to provide a window having two vertically slideable sashes arranged so that they may also be pivotally swung to open or closed position throughout a range of vertical positions of the sashes, each sash coating with a screen roller to screen any portion of the window opened by either sash, one of the sashes having means for wiping the glass of the other of the sashes, and for sealing the space between the sashes against the entrance of insects and dust, both of said sashes being counterbalanced on one side by a spring counterbalance and on the other side by a double pulley arrangement.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a front view of a window constructed in accordance with this invention, parts being broken away to show structure therebeneath.

Fig. 2 is a section on the line 2—2 of Fig. 1, but showing both sashes in section as if both sashes were in their lowermost positions in the window, a screen being shown in a slot.

Fig. 3 is a section on the line 3—3 of Fig. 1, a screen being shown similar to Fig. 2.

Fig. 4 is a section on the line 4—4 of Fig. 1.

Fig. 5 is a perspective view of a screen roller forming a part of the window of the present invention.

Fig. 6 is a fragmentary view of the top portion of the lower screen.

Fig. 7 is a fragmentary perspective view of the

2

top portion of the lower screen showing how it tilts when in use.

Fig. 8 is a fragmentary view of a portion of the window frame showing a groove and a portion of the screen showing how the screen tilts when in use.

Fig. 9 is a fragmentary section on the line 9—9 of Fig. 1.

Fig. 10 is a fragmentary perspective view of a portion of the glass wiper forming a part of one of the window sashes.

Fig. 11 is a side view of one of the spring counterbalances forming a part of the window.

Fig. 12 is a fragmentary perspective view of a side portion of one of the sashes.

Fig. 13 is a fragmentary front view of a portion of one of the sashes.

Fig. 14 is a fragmentary perspective view of two portions of one of the sashes pivoted at ninety degrees relative to each other.

Fig. 15 is a front view of a window with the lower sash raised showing the screen in operative position.

Fig. 16 is a fragmentary perspective view of the window with the lower sash swung open.

The window, according to this invention, comprises a frame 10 which is a largely conventional structure including a sill 11, a top face board 12, a left face board 13, a right face board 14, a bottom face board 15, a left inside board 16, a right inside board 17, a top inside board 18 and a bottom inside board 19. The inside of the window is shown in Fig. 1. The outside would be somewhat similar in appearance in accordance with usual practice in making window frames out of wood. That is to say, substantially the same face boards would be provided on the outside of the frame as on the inside.

Upper and lower sash guides 20 and 21 respectively are formed by an inside guide strip 22, an intermediate guide strip 23 formed in two pieces connected together by screws, and an outside strip 24, all secured to the boards 16 and 17 on opposite sides of the window in the usual manner. An upper sash 25 slides in guides 20 and a lower sash 26 slides in guides 21.

The two sashes are substantially identical in structure and therefore only the bottom sash will be described in detail, corresponding parts of the top sash being indicated by like references with an accent added and referred to only when it is deemed necessary to clarify the following description. The sash includes a left (viewing from the inside of the window as in Fig. 1) slide strip 27 and a right slide strip 28, the cross sectional shape of the wood from which the strips are made being clearly shown in Figs. 2 and 3. A glass-containing frame 29, which is similar to a conventional sash in many respects is pivotally secured to the two strips 27 and 28 by two oppo-

sitely disposed screws 30 adjacent the bottom of the sash. Strips 27 and 28 are wider than strips 22 and 24 so that the frame 29 is not concealed at all by strips 22 and 24, leaving frame 29 free to pivot. Strips 27 and 28 enable the sash to slide vertically in the manner of any ordinary window sash and the screws 30 permit the frame 29 to pivot relative to the strips 27 and 28 at any position that strips 27 and 28 may be slid to. This enables the frame 29 to be swung open for cleaning the glass or for ventilation, as shown in Fig. 16. The same is true, of course, of the top sash. However, the present invention is applicable to a single sash, or to a single sliding sash, window, as will be obvious.

Guides 27 and 28 each have a longitudinal shoulder 31 coacting with a corresponding shoulder 32 on the frame 29 permitting the frame 29 to swing in one direction (inward) to open position only and forming an airtight joint when the frame 29 is closed, airtight being used in the sense that ordinary windows are airtight when they are closed. Suitable means (not shown) may be provided for locking the glass-carrying frame to the strips 27 and 28 to act as a unit therewith if desired. Also the usual latch (not shown) will be provided for locking the two sashes together. A weather strip 33 is fastened by screws to strip 24 and fits in a slot 34 in the upper window strip 27'. A similar weatherstrip 33' is fastened by screws to strip 23 and fits in a slot 35 in strip 27. These are clearly shown in Fig. 2. Similar weatherstrips will be employed at the other side of the window, these strips not being shown in the drawings for simplicity.

The bottom part of the lower glass frame 29 is weatherstripped by a strip 36 coacting with a groove 37, best shown in Fig. 4.

The window as thus far described provides an upper and lower slideable sash, each of which is weatherstripped and each of which can be pivotally swung to open position as well as slid to open position.

A chamber 38 is provided on top of sill 11 and a chamber 38' is provided below board 18, these chambers being formed by suitable boards secured to the frame to box off the desired area and are covered by removable slide strips 38a which permits the interchanging of the rollers 39, all as is clearly shown in Fig. 4. A screen roller 39 is disposed in each of these chambers, each screen roller being wider than the adjacent frame 29 or 29' as will presently appear. The roller per se, detached from the window, is shown in Fig. 5. It includes a base 40 which may be secured to the appropriate portion of the window frame, end members 41 extending from the base ends in which is journaled a spring-actuated roller 42 similar to an ordinary window shade roller. No further description thereof being deemed necessary since their construction is generally known by those skilled in the art, a roll of wire screen 43 being fastened to the roller and wound thereon. The side edges of the wire screen are bound by tape 44 to provide for easy sliding as will presently appear and the top edge of the screen is secured to a strip 45 having wings 46 at either end. Two felt strips 47, each having an orifice 48, are secured to the strip 45 at the same side as the screen. Each of these strips 47 extends around the edge of the strip 45 to the other side and over this other side, extending beyond the other edge thereof as is clearly shown in Fig. 5. Thus the screen, which is secured to the top of the strip 45, pulls in one direction from the

top of the strip whereas the strips 47 pull in the opposite direction from the bottom of the strip, tending to turn it. The effect of this action is to tilt the strip 45 as shown in Figs. 7 and 8 for a purpose presently to appear.

Each of the rollers 39 is long enough so that the screen 43 extends the full width of the adjacent sash and therebeyond so that the taped ends of the wire and the wings 46 slide in slots 49 formed in the bottom half of strips 22. The top screen for the top sash similarly slides in slots 49' in strip 23.

The bottom board of the frame 29 is provided with two hooks 50 on its inside face. When the strips 47, by means of the orifices 48, are hooked to the hooks 50, the screen will automatically follow the lower sash 26 when it is raised, therefore screening the open window against entrance of insects. Of course the screen can also be raised and lowered independently of the sash if desired, or it may be left rolled up, as in winter. The upper screen acts in a similar manner. The wings 46 are tilted in an inclined position in the slots 49, as shown in Fig. 8, thereby resting against opposite sides of the slots 49 and sealing the slots against the entrance of insects or of dust and other foreign matter around the ends of the wings.

Base 40 has a slot 51 in which is disposed a felt strip 52 which rubs against the wire screen as shown in Fig. 5, preventing passage of insects or foreign matter between the screen and the base as the screen is rolled or unrolled.

Another feature of the window of the present invention is that a strip 53 is secured to the lower edge of the top sash and rubs against the glass of the bottom sash at the outside (see Fig. 4) thereof, and against the adjacent wood sides, for wiping this glass, and wood sides as the sashes are moved relative to each other and for sealing the space between the sashes against the passage of insects or foreign matter into the space between the sashes when either or both are open. Strip 53 is formed of a slotted base 54 and a felt insert 55, best shown in Figs. 9 and 10, and is cut away at the ends to fit around the wood of frame 29.

The two sashes of the window are counterbalanced in a novel manner. A spring counterbalance 56 is secured to the board 17 at the top of the upper sash, its flexible cable being secured to the top of the bottom sash. Similarly another spring counterbalance, identical with the counterbalance 56, but not shown in the drawing, is secured immediately behind the counterbalance 56 and secured to the top of the top sash. These counterbalances are of well known construction and no detailed description thereof is deemed necessary. One is shown per se in Fig. 11. However, such counterbalances are not provided on the left side of the sashes. Each sash is counterbalanced on its left side by a double pulley arrangement, as follows:

Strips 27 and 27' at the left side of the sashes are each provided at its middle and in the outer face thereof with a recess 57 in which is disposed a pulley 58 having a spool 59 formed with adjacent tracks 60. The pulley is rotatively secured to the strip 27 (or 27') by a screw 61. A slot 62 is formed in one side of the strip above the pulley and a slot 63 is formed in the other side of the strip below the pulley. Cables 64 each have one end secured in one of said tracks and wound in their respective tracks, each in an opposite direction so that when the pulley turns in one direction or the other one cable will be unwound while

the other cable is wound on the spool 60 and one extends therefrom through the slot 62 and the other extends through the other slot 63, one cable has its free end secured to the top of the window frame and the other has its free ends secured to the bottom of the window frame.

The counterbalance system operates as follows:

Considering the lower sash by way of example, it being understood that the upper sash operates in a similar manner, when the lower sash is raised, the spring counterbalance 56 winds up aiding in the raising of the lower sash. However, as there is a spring counterbalance 56 at only one side of the sash, if this were all that was provided the sash would not raise evenly but would bind in the frame. Also, the spring counterbalance would pull the sash all the way up and there would be no way to hold the sash in any desired partial window-opening position. However, the cables 64 provide for this. At the same time that the spring counterbalance winds up, one cable 64 is wound up on the spool in its track while the other cable 64 is unwound from the spool in its track. There is no tendency of either cable to wind or unwind by itself and therefore both cables, due to their inherent action and to friction, resist the pull of the spring counterbalance and counteract its tilting and raising effect to the extent desired to hold the sash in any desired position and to keep the sash square in the frame, while nevertheless permitting the sash to be easily raised and lowered. This counterbalance arrangement does away with the well known type of counterbalance sash weight and all of its accompanying difficulties such as the breaking of sash cords and the taking apart of the window frame to replace them. The cable 64 is made of woven steel and is flexible and strong, insuring long life. However, should it break, it is only necessary to remove the sash from the window to replace it and not to take part of the frame apart.

From the foregoing description it will be seen that the present invention provides a novel window having many desirable characteristics not present in ordinary every day window construction. In a simple construction a window is provided having two vertically slidable sashes, each of which can pivot to open position at any vertical position that it is in, the sashes being weather-stripped and counterbalanced by a simple and compact arrangement. Furthermore the window includes as a part thereof screens for both the top and bottom sashes which screens are concealed from sight when not in use and may be hooked to the sashes for automatic operation when desired, thus doing away with separate screens which must be stored in winter. The window has many other useful features as were previously set forth. It will be obvious that the many advantageous characteristics of the window described have application to other types of windows than two sash windows, many of these features being adaptable equally as well to a single sash window.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new and desire to secure by United States Letters Patent is:

1. A window comprising a frame having a compartment at one end, an actuatable roller disposed in said compartment, a roll of wire screen wound on and secured to said roller, a strip secured to the free end of said screen, said wire screen being secured to said strip on one side thereof adjacent the edge thereof remote from said roller, two tabs secured to said strip adjacent the other edge thereof, and extending upwardly beyond said first mentioned edge on the other side of said strip, said strip having wings at its ends and said frame having slots in which said wings are adapted to slide, said wings being wider than said slots facilitating tilting of said wings to bear against opposite sides of said slot, a sash slidably disposed in said frame, and means for securing said tabs to said sash for winding and unwinding of said screen with movement of said sash.

2. A window comprising a frame having a compartment at one end, an actuatable roller disposed in said compartment, a roll of wire screen wound on and secured to said roller, a strip secured to the free end of said screen, said wire screen being secured to said strip on one side thereof adjacent the edge thereof remote from said roller, two tabs secured to said strip adjacent the other edge thereof, and extending upwardly beyond said first mentioned edge on the other side of said strip, said strip having wings at its ends and said frame having slots in which said wings are adapted to slide, said wings being wider than said slots, and being tiltable therein to bear against opposite sides of said slot, a sash slidably disposed in said frame, and means for securing said tabs to said sash for winding and unwinding of said screen with movement of said sash, said attachment of said tabs inwards of the free edge thereof insuring tilting of said strip engaging the wings against the sides of the slot when the sash is moved.

3. A window comprising a frame having a compartment at one end and slots at the sides thereof and slidably supporting sash, an actuatable roller disposed in said compartment, a roll of wire screen wound on and secured to said roller and adapted to have sides guided by said slots when extended from said compartment, a strip secured to the free end of said screen and having wings engaging said slots, and means connecting said strip to said sash to extend said screen from said compartment when said sash is moved to an open position and simultaneously tilt said strips to cause its wings to bear against opposite sides of said slots in all extended positions of said screen.

LOUIS ROYAK.
